UNITED STATES PATENT OFFICE.

WILLIAM SCHOLES, OF PHILADELPHIA, PENNSYLVANIA.

TWISTING-MACHINE.

1,391,512.

Specification of Letters Patent. Patented Sept. 20, 1921.

Application filed November 8, 1916. Serial No. 130,129.

To all whom it may concern:

Be it known that I, WILLIAM SCHOLES, of Philadelphia, in the county of Philadelphia and State of Pennsylvania, have invented 5 certain new and useful Improvements in Twisting-Machines, whereof the following is a specification, reference being had to the accompanying drawings.

The invention relates to machines commonly known in the textile trade as "twisters," whereby yarns or paper ribbons are twisted into twine in preparation for weaving.

The present improvement is not only directed to means for performing the twisting operation, but also comprehends mechanism for simultaneously winding the twisted material into cops, so as to be in the proper form for use in the shuttles of looms, etc.

20 Heretofore, it has been customary to perform the twisting upon one machine, whereby the twisted twines were wound upon spools, and the latter subsequently transferred to another machine commonly termed 25 a "cop winder."

A further object of the present invention is to provide a construction whereby there is produced a relative twisting movement between the roll of material and the crushing 30 eyelets while the material is being drawn therethrough by the receiving spindle, so as to give the material a very tight twist before it is crushed and attenuated by the crushing means.

35 According to my invention, I combine these two functions, thereby obviating the necessity for the two separate stages above noted, and effecting a decided decrease in the cost of manufacture.

40 The present improvement also comprehends a novel and simplified mechanism for producing the twisting, which mechanism is so coördinated with devices for cop winding that both may be automatically rendered 45 inactive upon the completion of a cop.

In the accompanying drawings, Figure I, is a transverse sectional view of a machine conveniently embodying my invention.

45 Figs. II, and III, are detail views on an 50 enlarged scale, showing the means for gradually crushing and attenuating the paper ribbon during the twisting operation.

The machine embodying my improvements comprises a main driving shaft 1, which, through a belt 2, transmits motion to a pulley 3. Said pulley is fixed upon the drive sleeve 5, for the spindle 6, upon which the cop indicated at 7, is wound. Sleeve 5, is journaled in bearings 8, and 9, mounted upon the supporting frame 10, of the machine, 55 and is adapted to receive the squared portion 11, of the spindle. By this arrangement positive rotation is imparted to the spindle while the latter may at the same time shift longitudinally as the material accumulates 60 thereon in the formation of a cop.

Coöperating with the spindle, is a winding cone 12, mounted in the end of a bifurcated arm 13. Said arm is loosely fulcrumed about a rod 15, fixed in the frame of the machine, 70 and a spring 16, serves to keep the winding cone in proper operative position with relation to the spindle 6, and is further functional in allowing the arm 13, to be sufficiently withdrawn by the operator to permit the removal of a completed cop. As the material builds on the spindle, the winding cone is instrumental in causing the spindle to be shifted inwardly until the collar 17, thereon engages the trip 18, which controls the shifting of the belt 2, from the tight pulley 3, on the sleeve 5, to the loose pulley 19, directly adjacent. The trip 18, is freely fulcrumed about a fixed supporting rod 20, and in the position shown in Fig. I, arrests the collar 85 21, on the shifter rod 22, and locks the latter against the pressure of the spring 23, which normally tends to shift the belt 2, to the loose pulley 19, the extent of shifting being determined by a buffer collar 25. The shifter 90 rod 22, terminates in a hand knob 26, whereby the parts may be manually restored to driving position in beginning a new cop.

A feeding device is also operatively associated with the spindle and winding cone. 95 This device is in the form of an oscillating lever 27, the amplitude of its oscillation corresponding in extent to the length of the cone. Lever 27, finds its fulcrum about the rod 15, already described and is maintained, by means of a spring 28, in engagement with a cam 29, mounted upon a longitudinal shaft 30, which is driven by a belt 31, from the main shaft 1.

The paper to be twisted is prepared in rolls of narrow ribbon such as indicated at 32, which have previously been moistened and which, according to my invention, are supported upon a rotating table 33, provided with a center pin 35, and maintained, by gravity, in frictional contact with a disk 36. This disk is rotatively supported in the transverse portion 37, of the frame of the machine, and is integrally formed with a sheave 38, which is also driven from the main shaft 1, by a belt 39.

The table 33, is preferably rotated in a direction corresponding with the natural curl of the paper occasioned by being unwound from the center of the roll. After passing over the guide rolls 40, and 41, mounted upon a suitable supporting stem 42, the ribbon is directed through a series of stationary crushing and attenuating eyelets 45, 46, and 47, preparatory to being wound upon the spindle in the formation of the cop. As best shown in Figs. II, and III, these eyelets are supported in arms 48, which are vertically adjustable upon the stem 42. It is also to be noted that the bore of the eyelets is successively decreased so that a gradual crushing and attenuation is effected, while the twisted ribbon is drawn by virtue 30 of the rotation of the spindle.

It will also be seen that because of the relative twisting movement between the roll and the crushing eyelets, which movement is given in the direction of the natural unwinding of the ribbon from the roll, there is effected a very tight wrapping of the ribbon before it reaches the eyelets where it is given a permanent set as it passes therethrough.

While I have shown three eyelets in the illustrations, it is of course to be understood that I do not wish to be thus limited, since this number and the successive gaging, may be varied, not only in accordance with the width of the ribbon, but also with the kind 45 of material to be twisted.

The ample length of the strand of paper ribbon constantly maintained between the guide roll 40, and the supporting table 33, is such as to permit an automatic compensation between the successive convolutions of the spiral created through the rotations of the said table, whereby a twist of substantially even pitch is effected before the crushing is accomplished. The pitch of the twist 55 may obviously be varied indefinitely by changing the speed ratios between the rotation of the supporting table 33, for the roll of material, and that of the winding spindle.

In order that the supporting table may be simultaneously stopped with the winding spindle at the completion of a cop, I have provided a brake which is automatically operated in conjunction with the shifting mechanism for the belt 2. The said brake is in the

form of a bell crank lever 50, pivoted about 65 a fixed fulcrum rod 51, and provided with a wear-resisting pad 52, adapted to engage with the periphery of the table 33. The other arm of bell crank 50, is coupled by means of a link 53, to an oscillating lever 55, 70 having a finger 56, which is normally engaged by a pin 57, on the shifter rod 22, to release the brake in opposition to the pull of the coiled spring 58.

In operation, the longitudinal motion of 75 the shifter rod causes the release of the lever 55, so that the brake is automatically applied through the instrumentality of spring 58, to prevent further rotation of the table simultaneously with the shifting of the belt 2, to 80 the idle pulley 19, in rendering the winding spindle inactive. Thereupon, the operator may remove the completed cop, draw the spindle forward as far as allowed by its terminal collar 60, and reset the belt shifter 85 and the parts controlled thereby, by means of the hand knob 26. The machine will then be in condition for beginning a new cop.

While I have shown the organization herein described as confined to the winding of a 90 single cop, it is of course to be understood that the same may be compounded indefinitely in a machine for producing multiple windings, without deviating from the scope of my invention.

While I have described my invention as particularly adaptable in twisting and winding paper ribbon, it is, of course, to be understood that the same is applicable in treating other materials of similar nature, in accomplishing like results.

I do not herein claim the process claimed in my Patent No. 1,363,279, granted December 28, 1920, on an application copending with this, although here disclosed as a mode 105 of use of the apparatus herein claimed.

Having thus described my invention, I claim:

1. In a machine for forming flat ribbon into twine, the combination of stationary 110 crushing eyelets, and means comprising a rotary winding spindle for drawing the ribbon from a supply roll with a twist and through the eyelets against their crushing resistance, so as to wind it in the form of compact 115 twine.

2. In a machine for forming flat ribbon into twine, the combination of stationary crushing eyelets, and means comprising a rotary spindle in line with said eyelets for receiving and winding the ribbon directly from them, said spindle first drawing the ribbon from a supply roll with a twist and then through the eyelets.

3. In a machine for forming flat ribbon 125 into twine, the combination of a support for the supply roll, stationary crushing eyelets, and a rotary winding spindle drawing the

ribbon from the supply roll and through the eyelets with a twist, the parts being so arranged as to leave a considerable length of ribbon free and unengaged between eyelets and supply roll so as to permit free self-adjustment of the ribbon and equalization of the twist therein.

In testimony whereof, I have hereunto signed my name at Philadelphia, Pennsylvania, this fourth day of November 1916.

WILLIAM SCHOLES.
